ATTORNEY'S

UNITED STATES PATENT OFFICE.

MAHLON M. ZELLERS, OF KENT, OHIO.

MACHINE FOR MAKING BUTTON-FASTENERS.

SPECIFICATION forming part of Letters Patent No. 284,158, dated August 28, 1883.

Application filed September 21, 1882. (No model.)

To all whom it may concern:

Be it known that I, MAHLON M. ZELLERS, of Kent, in the county of Portage and State of Ohio, have invented certain new and useful Improvements in Machines for Making Button-Fasteners; and I do hereby declare the following to be a full, clear, and exact description of the invention, such as will enable others skilled in the art to which it pertains to make and use the same.

My invention relates to a machine for making button-fasteners; and it consists in the parts and combination of parts as will be hereinafter fully set forth and claimed.

In the drawings, Figure 1 is an isometric view of my machine. Fig. 2 is a plan view of the same. Fig. 3 is a longitudinal vertical section taken through the wire-feeding mechanism of my machine. Figs. 4, 5, 6, 7, and 8 are enlarged views, in section, of some of the parts of my machine, showing more clearly their construction and operation. Fig. 9 is a view of the button-fastener as formed by my machine.

Referring first to Fig. 9, the letter T² indicates a button-fastener such as my machine is designed to produce; and it consists of a loose convolute coil or spiral, t, of wire, having its inner end portion projecting axially or at right angles to its plane, and bent to form a loop, t', which is intended to engage the eye of a button. In using such a fastener a small hole is formed in the material to which it is to be attached, and the loop being held between the finger and thumb, the outer end of the spiral is inserted through the hole, and the fastening is then turned to force said spiral through the material coil by coil until the inner end of the loop comes into the hole. The fastening may be removed by turning it in an opposite direction from that required to insert it. Such a fastener possesses an advantage that it is readily attached and removed, and no tool or machine is required in setting or securing it in place.

A is the bed of my machine.

B is a shaft, which is journaled in suitable bearings extending upward from one end of the bed A.

C is a crank-wheel, which is secured to one end of the shaft B.

D is a pitman, which is operated by the

crank-wheel C, being connected thereto by means of the wrist or pin a.

E is a slide, which is connected to and reciprocated by the pitman D. This slide E is provided with a lug, b, which extends upward from said slide.

E' is another slide, which is provided on its upper face with a rack, c. One end of this slide E' is provided with an extension or spindle, E'', which passes through a hole in the lug b.

F is a slotted plate, which is secured to the slide E and reciprocates with said slide. The slot d of the plate F is set at an angle to the direction in which the slide moves or reciprocates.

G is a frame or guide of the feeding device of my machine, and is provided at one end with a guide, e, through which the wire passes.

G' is a series of straightening-rolls, which follow after the guide e, and through which the wire also passes and is straightened.

H is a slide, which moves in the frame or guide G. This slide H is provided with a grasping device, the upper jaw of which is rigidly secured to the slide H, and the lower jaw, g, is pivotally attached to the slide. The free end of the lower jaw, g, is provided with an arm, g', which is set at a right angle to said jaw, and its lower end being adapted to engage with the slot d in the plate F. The slot d in the plate F acts as said plate is reciprocated to reciprocate the slide H through the arm g' of the jaw g, and it will also be noticed that as the slot is acting to move the slide H toward the machine it will also act to close the jaw g against the jaw f, and thus clamp the wire which passes between said jaws, as shown in Fig. 3, and when the plate F is moved in the opposite direction the slot d will act to open the lower jaw, g, away from the upper jaw, f, and thus release its hold on the wire, thus allowing the jaws to move back from the machine without carrying the wire back. The lower jaw, g, is prevented from opening too far

by providing it at its pivoted end with a hook-shaped projection, h, which engages with a pin, h'. (See Fig. 3.) The slide H is also provided with two guides, H' and H'', one at either end of the said slide, the guide H' acting to guide the wire to the grasping device, and the other guide, H'', acting to guide the wire away

from the grasping device. (See Fig. 3.) These guides H' and H^2 are secured in lugs which extend out from the face of the slide H , as shown.

5 I is a guide-holder, which is pivoted at one end to the frame G . (See Fig. 3.) The free end of the guide-holder I is guided between the uprights $I' I'$, (see Fig. 4,) and supported on the movable wedge-shaped piece I^2 , which 10 passes through the uprights $I' I'$ under the die-holder I, and at a right angle to it. (See Figs. 3 and 4.)

J is a guide, which passes through the guide-holder I from one end to the other of 15 said holder, and is made hollow to allow of the passage of the wire, as shown in Fig. 3.

K is another hollow guide, having its passage directly opposite the passage in the guide J and its one end contiguous to one end of the 20 guide J. (See Fig. 3.) The guide K is held rigidly in place by means of its holders $K' K^2$; but the guide J, with its holder I, is adapted to be reciprocated vertically by means of the 25 wedge-shaped piece I^2 , an adjustable spiral spring, i , acting to keep the guide-holder in contact with the wedge-shaped piece I^2 . (See Fig. 4.) The upward movement of the guide J acts to cut or separate the wire at the point where the guides J and K touch. The wedge-shaped piece I^2 is reciprocated by means of a 30 rod, M' , one end of said rod M' being pivoted to the piece I^2 at j , and the other end being pivoted to the yoke M . The guide K extends from the guide-holder K' through the guide-holder K^2 . Near the outer end of the guide K I remove its upper portion, and provide instead a hinged piece, L, which is held in 35 position down against the lower surface of the guide K by means of a spring, L' , as shown in Fig. 3. The object in providing the hinged piece L will be hereinafter explained.

N is a cam-wheel, which is secured to the 40 shaft B (see Fig. 7) and adapted to engage with a friction-roller, k , secured to the yoke M . This cam-wheel N acts to drive the yoke M forward, and with it the shaft O, which is 45 adjustably secured to the said yoke M by means of the connecting-piece O' . (Shown more clearly in Fig. 6 at the right, which will 50 be readily understood.)

l is a spiral spring, one end of which is secured to the rear of the yoke M , and the other end is secured to a bracket, m , which extends out from the bed A. The function of this 55 spring is to pull back the yoke M and shaft O, and keep the roller k in contact with the cam-wheel N. The forward end of the shaft O is provided with a recess, into which is inserted a spindle, O^2 . (See Fig. 6 at the left.)

60 The spindle O^2 is in turn provided at its end with a punch, n , which is removably secured in the end of the said spindle in any suitable manner, one well-known manner being shown in Fig. 6, (at the extreme left,) which 65 consists of the split tapering end and conical cap fitting over the same and tightened by means of a screw-thread.

R is a shaft, which is journaled in bearings extending up from the bed A, and provided at one end with the bevel-pinion R' , which 70 meshes with the bevel-gear R^2 on the shaft S. This shaft S is driven or revolved in the direction of the arrow, Fig. 1, by means of the rack e on the slide E' and the pinions S' . (See Figs. 1 and 2.) Thus rotary motion is imparted in 75 one direction to the shaft R by means of the crank-wheel C, pitman D, slides E and E', rack e , pinion S' , shaft S, bevel-gear R^2 , and bevel-pinion R' . The reverse motion is imparted to the shaft R by means of a spring, T, 80 (see Figs. 1 and 2,) which is secured at one end to the shaft R in such a manner as to be wound up as the shaft is revolved by means of the crank C, &c., as hereinbefore mentioned. This reverse motion of the shaft R acts through 85 the bevel-pinion R' , bevel-gear R^2 , shaft S, pinion S' , and rack e to return the slide E' to the position shown in Fig. 1, so as to be acted upon again by the slide E. Thus it will be seen that by means of the crank C and intermediate 90 mechanism described, and the spring T, a rotary reciprocating motion is imparted to the shaft R. To prevent the spring T from turning the shaft R too far, I provide a check, S^2 , 95 which is secured to the shaft S, (see Fig. 8,) and engages with a pin, V, extending up from the bed A. The end of the shaft R which is nearest the feeding device is provided with a recess, into which fits a spindle, U. (See Fig. 5.) This spindle U is provided with a hollow 100 head, U' , into which fits and is secured a die, U^2 . The face of the die U^2 is slotted at p of sufficient width and depth to admit of the 105 passage of the wire in the manner shown in Fig. 3.

r is a punch, which is located in the spindle U in the rear of the die U^2 , one end of said punch passing through a hole formed in the 110 said die U^2 . This punch is actuated by means of a spiral spring, and acts to force the fastener out when it is finished, as will be herein-after fully explained.

s is a piece of spring metal, which extends upward from the bed A, and is provided with a hole, through which the punch n passes. The 115 function of this spring will also be fully explained in the operation of the machine hereinafter.

The operation of my machine is as follows: The end of a roll of wire is now passed through the hole in the guide e , and from thence through the straightening-rolls $G' G'$, and through the guide H' , clasping device f and g , guide H^2 , and guide J, until the end of the wire has reached the guide K. Now, rotary motion is imparted 120 to the shaft B by any suitable means, which in turn, through the mechanism hereinbefore described, imparts motion to the different parts of the machine.

I will start by describing the operation of 130 the feeding and cutting-off mechanism of my machine.

The pitman D acts with the crank-wheel C to impart a reciprocating motion to the slide

E, and through said slide E to the plate F, which is secured to the slide E. Now, as this plate F is reciprocated, the direction of the slot *d* is such that it acts through the arm *g* to operate the grasping device *f* and *g*, and also reciprocate the slide H, opening the jaws of the grasping device when the slide H is moved toward the left, Fig. 3, and closing the jaws when the slide H is moved toward the right. This acts to feed the wire along toward the right or to the machine, each stroke or movement to the right of the slide H acting to feed a certain length of wire which is cut off by the upward movement of the guide J, the mechanism operating said guide J being so timed that it will raise the guide J and cut the wire off only while the slide H and grasping device *f* and *g* are moving back or to the left, thus allowing the passage of the guide J to be opposite or on a level with the passage of the guide K, so that at the next forward (to the right) movement of the slide H and grasping device *f* and *g* the lengths of wire in the guide K are moved along and fed to the die U², a short distance of one end of the lengths of wire only being fed into the slot *p* of the said die U².

The operation of the loop forming and twisting mechanism of my machine is as follows: As the end of the wire is fed into the slot *p*, the cam-wheel N has acted to drive the spindle O forward, and with it the punch *n*. This punch *n*, as it is driven forward, forces the end of the wire into the die U², and thus forms the loop *t* of the fastener. Now, as the punch *n* is driven forward it carries with it the spring-piece *s*. This punch *n* and spring-piece *s* are held in this position by means of the cam on the cam-wheel N (the shape of which is shown in Fig. 7) until the lug *b* has acted on the slide E', which, as hereinbefore shown, imparts rotary motion to the shaft R and through it to the die U². The motion of the shaft R and die U² is in the direction of the arrow, Fig. 3, and acts to form the spiral *t* of the fastener, the face of the spring-piece *s* acting as a guide to hold the wire from any lateral movement. It will be noticed that the upper part of the guide K is provided with a pivoted piece, L. The function of this pivoted piece is to hold and feed the wire as it is being wound or formed into a spiral, the tension of the spring L' being sufficient to overcome the tension of the wire and hold it down. The punch *n* is now withdrawn by means of the spring *l*, the cam or projection on the cam-wheel N having passed over the roller *k*. Now, as the punch *n* is pulled back or with-

drawn, the tension of the spring T' on the punch *r* in the die U² causes the said punch *r* to force the finished fastener out of the slot *p*, and thus the said die is ready for another operation.

What I claim is—

1. In a machine for forming button-fasteners, the combination, with the wire-grasping device, having an arm extending therefrom and means for supporting it, of the reciprocating slotted plate, and mechanism for imparting motion to the plate at an angle to the line of the slot, the said arm and slot being adapted to engage each other, whereby motion is given to the grasping device at right angles to that of the plate, substantially as described.

2. In a machine for forming button-fasteners, the combination, with the slide E and the reciprocating plate attached thereto and actuated thereby, having a slot at an angle to its line of motion, of the wire-grasping device, one of the jaws of which having a pin which engages with the slot of said plate, whereby the grasping device is reciprocated and opened and closed, substantially as described.

3. The combination, with the wire-feeding device, of a stationary guide, and a pivoted guide-holder having a guide secured therein, and a wedge for operating the pivoted guide-holder and cutting the wire, substantially as set forth.

4. The combination, with the feeding device, of the die constructed and adapted to coil the wire to form a spiral, means for actuating said die and the reciprocating punch to form a loop in the wire, substantially as set forth.

5. In a machine for forming button-fasteners, the combination, with the crank C and pitman D, of the slides E and E', the pinion S', the shaft S, the shaft R, and suitable gearing for imparting motion thereto, substantially as shown and described.

6. In a machine for forming button-fasteners, the combination, with the shaft R, having a pinion, R', the shaft S, having a beveled gear, R², and a pinion, S', and the rack-bar *c*, of the spring T, wound around the shaft R and secured to the bed-plate A, substantially as shown and described.

In testimony whereof I have signed my name to this specification in the presence of two subscribing witnesses.

MAHLON M. ZELLERS.
